UNITED STATES PATENT OFFICE

96,653

DESIGN FOR A COMBINATION ASH TRAY AND CIGAR LIGHTER

Irving Florman, New York, N. Y.

Application July 9, 1935, Serial No. 57,578

Term of patent 7 years

To all whom it may concern:

Be it known that I, Irving Florman, a citizen of the United States, residing at New York, in the county of New York and State of New York, have invented a new, original, and ornamental Design for a Combination Ash Tray and Cigar Lighter, of which the following is a specification, reference being had to the accompanying drawing, forming a part thereof.

Fig. 1 is a plan view of a combined ash tray

and cigar lighter embodying my new design.

Fig. 2 is a side view of the same, part of the device being indicated in section to illustrate the profile.

Fig. 3 is an isometric view of my design.

I claim:

The ornamental design for a combination ash tray and cigar lighter, as shown.

IRVING FLORMAN.
